UNITED STATES PATENT OFFICE.

ANDREW J. SANFORD, OF NEWARK, OHIO, ASSIGNOR TO A. H. HEISEY & CO., OF
NEWARK, OHIO.

DESIGN FOR A JAR.

43,437.

Specification for Design.

Patented Jan. 7, 1913.

Application filed October 10, 1912. Serial No. 725,057. Term of patent 14 years.

To all whom it may concern:

Be it known that I, ANDREW J. SANFORD, a citizen of the United States, residing at Newark, in the county of Licking and State of Ohio, have invented a new, original, and ornamental Design for Jars, of which the following is a specification, reference being had to the accompanying drawing, forming part thereof.

The figure is a perspective view of a jar, showing my new design.

I claim:

The ornamental design for a jar, as shown.

ANDREW J. SANFORD.

Witnesses:

MAUDE BOTT,
HERBERT L. BAKER.
